UNITED STATES PATENT OFFICE.

HENRY R. ROHR, OF BUCKHANNON, WEST VIRGINIA.

CURTAIN POLE.

1,406,685.

Specification of Letters Patent. Patented Feb. 14, 1922.

Application filed April 10, 1919. Serial No. 288,965.

To all whom it may concern:

Be it known that I, HENRY R. ROHR, a citizen of the United States, and resident of Buckhannon, in the county of Upshur 5 and State of West Virginia, have invented certain new and useful Improvements in Curtain Poles, of which the following is a specification.

This invention relates to curtain poles, 10 and an object of the invention is to provide a pole for supporting lace curtains or analogous curtains which is simple in construction, may be manufactured for a relatively small cost, and which is attractive in appearance.

Another object of the invention is to provide a curtain pole as specified, which includes a tubular body formed of sheet metal or any analogous material provided with 20 a slot extending longitudinally therein, throughout its entire length, the edge portion of said tubular member along said slot being rolled inwardly to provide spaced overhanging flanges, adapted to be frictionally engaged by spaced overhanging flanges formed upon supporting members which are slipped into the tube from each end of the same, and are positioned adjacent the ends of the tube, forming means for supporting 25 30 35

a pin or rod within the tubular member to which pin or rod, the curtains are attached, by means of resilient clips, thereby permitting the easy connection with or disconnection from the curtain carrying rod of a curtain and eliminating the necessity of hemming the upper edges of the curtains to slip over the rod or the use of unsightly rings such as are commonly employed for connecting curtains to their carrying rods.

40 Other objects of the invention will appear in the following detailed description taken in connection with the accompanying drawings, forming a part of this specification, and in which drawings:

45 Figure 1 is a side elevation of the improved curtain pole.

Figure 2 is a cross section taken on the line 2—2 of Figure 1.

50 Figure 3 is a longitudinal section through the curtain pole.

Figure 4 is a fragmentary perspective view through the tubular body of the curtain pole.

Figure 5 is a detail perspective view of

the rod supporting saddle which is slidably connected to the tubular body.

Figure 6 is a detail perspective view of the resilient clips employed for retaining the curtain upon its carrying rod, and

Figure 7 is a fragmentary side elevation 60 of a modified form of the pole, the same being adapted for supporting a towel or analogous article.

Referring more particularly to the drawings, wherein like characters indicate like 65 and corresponding parts, 1 indicates a tubular body of the pole which is constructed of sheet metal or analogous material, and is provided with a slot or opening 2 extending longitudinally therein and throughout its 70 entire length, the edge portions 3 and 4 of the tubular body along side of the opening 2 are inturned forming spaced flanges, which are engaged by the inturned flanges 5 and 6 respectively of the supporting saddles 7. 75 These saddles 7 are also formed of sheet metal and are slightly arcuated transversely as clearly shown in Figures 2 and 5 of the drawings to form supports for the relatively small rod 8 which is placed within 80 the tubular body 1. The ends of the tubular body 1 are normally open, and removable caps 9 and 10 having annular flanges 17 upon their outer ends are provided for mounting upon said open ends, after the 85 relatively small rod 8 has been placed within the tubular body 1. The curtains, indicated at A, have their upper edges looped over the carrying rod 8, as clearly shown in Figure 2 of the drawings, and they are held 90 in said looped positions by means of spring clips 11. The spring clips 11, are formed of resilient material and shaped to provide a pair of spaced sections 12 and 13, the terminals of which curve outwardly as shown 95 at 14, to facilitate the spreading of the members 12 and 13 for positioning the clips 11 over the rod 8 and the portion of the curtain A which is looped thereover.

The pole structure may be supported in 100 any suitable manner, but in the example shown is supported adjacent a window frame, by means of brackets, generically indicated by the numeral 20. These brackets 20 comprise attaching portions 21 and 22 105 provided with transverse flanges 23, through which the screws or analogous attaching devices extend for fixing the brackets to the

window frame or analogous support. The support or attaching arm 22 has an arcuate portion 24 formed upon its end opposite to the flange 23, and this arcuate edge is adapted for engagement about the under surface of one of the caps 9 or 10 upon the end of the tubular body 1. The attaching arm 21 has an arcuate portion 25 formed thereon, which curves downwardly, and is attached to 10 a portion of the arcuate portion 24 near the attaching leg 22 as clearly shown at 26 in Figure 2 of the drawings. The arcuate portion 25 engages about the inner part of the circumference of the tubular body 1. An 15 arm 27 is attached, in any suitable manner to the attaching leg or arm 21, and it is provided with an arcuate portion 28 which is bent over the uppermost portion of the circumference of the shaft. This arcuate portion 28 has its terminal curved upwardly as 20 shown at 29 and provided with an opening extending therethrough, which receives a tongue 30 formed upon the free end of the arcuate portion 24. The tongue 30 is formed 25 by reducing the width of the terminal of the arcuate portion 24 and it is bent or curved outwardly so that when inserted through the opening in the terminal 29 it will, owing to its inherent tendency, spring outwardly, and 30 securely connect the arcuate sections 24 and 28 to support the curtain pole. The caps 9 and 10 have annular flanges 17 upon their outer ends to prevent longitudinal sliding movement of the curtain pole out of the supporting bracket structure 20.

In Figure 7 of the drawings, a modified form of the invention is shown, this modified form being provided for supporting cowls or analogous structures and it differs from 40 the preferred embodiment, only in the name plate 40 which is attached, in any suitable manner, to the tubular body 1^a intermediate of its ends. This name plate 40 may be utilized for advertising purposes, or in cases 45 where a towel service is employed, it could be used to carry the name of said towel service.

Changes in details may be made without departing from the spirit of this invention, 50 but;

I claim:

1. In a curtain pole, the combination of a tubular body provided with a longitudinally extending opening, the edges of the body at 55 said opening being bent inwardly to form flanges, supporting saddles adapted to be placed within the tubular body in spaced apart relation and having their edges bent to engage the flanges thereof and a curtain

carrying rod supported upon said saddles that a curtain may hang therefrom between said saddles. 60

2. In a curtain pole, the combination of a tubular body provided with a longitudinally extending opening, the edges of the body at 65 said opening being bent inwardly to form flanges, supporting saddles adapted to be placed within and in close proximity to the ends of the tubular body and having their edges bent to engage the flanges thereof, a curtain carrying rod inserted within said tubular body and having its ends resting upon said supporting saddles that the curtain may hang upon its length between the 70 saddles, and means for holding the curtain 75 upon said carrying rod.

3. In a curtain pole, the combination of a tubular body having open ends and provided with a longitudinally extending opening, the edges of the body at 80 said opening being bent inwardly upon themselves to form flanges, supporting saddles adapted to be placed within and at the ends of the tubular body and having their edges bent back upon themselves to slidably interengage the flanges 85 thereof, a curtain carrying rod inserted within said tubular body and having its ends resting upon the supporting saddles that the curtain may hang upon its length between the 90 saddles, and caps closing the ends of said 95 tubular body.

4. In a curtain pole, the combination of a tubular body having open ends and provided with a longitudinally extending opening, the edges of the body at 100 said opening being bent inwardly upon themselves to form flanges, supporting saddles adapted to be placed within and at the ends of the tubular body and having their edges bent back upon themselves to slidably interengage the flanges 105 thereof, a curtain carrying rod inserted within said tubular body and having its ends resting upon the supporting saddles that the curtain may hang upon its length between the 110 saddles, caps closing the ends of said 115 tubular body and resilient clips adapted to be positioned on said carrying rod for clamping the curtain thereto.

5. In a curtain pole, the combination of a tubular body provided with a longitudinally 110 extending slot open at the ends thereof, supporting saddles adapted to be placed within said tubular body and adjusted to rest in spaced apart relation within the tubular body and a curtain carrying rod supported 115 upon said saddles that a curtain may hang therefrom between said saddles.

HENRY R. ROHR.
